United States Patent Office

Des. 220,883
Patented June 8, 1971

220,883

MIXER

Norman A. Steinkamp, Chicago Heights, Ill., assignor to Sunbeam Corporation, Chicago, Ill.

Filed May 8, 1970, Ser. No. 22,888

Term of patent 14 years

Int. Cl. D7—05

U.S. Cl. D44—1

FIG. 1 is a perspective view of a mixer showing my new design;

FIG. 2 is a side elevational view thereof;

FIG. 3 is a top plan view thereof;

FIG. 4 is a front view thereof;

FIG. 5 is a rear view thereof;

FIG. 6 is a bottom view thereof; and

FIG. 7 is a sectional view taken on line 7-7 of FIG. 4. I claim:

The ornamental design for a mixer, as shown.
